UNITED STATES PATENT OFFICE

NASEEB A. NADDAFF, OF BOSTON, MASSACHUSETTS

INDICATOR

Application filed September 10, 1930. Serial No. 481,026.

My present invention has reference to a mail box for use in apartment houses, rooming houses, or other places where a number of persons dwell in the same domicile, and my object is the provision of a safety mail box in which the front is provided with a letter receiving slot and any desired number of sight openings, the rear of the front having guided thereon a slidable gravity influenced plate which carries cards of the dwellers of the residence as well as the name of the housekeeper or manager, and whereby the mailman will have knowledge of the several occupants of the dwelling without necessitating the making of inquiries and who after the mail has been deposited in the box operates a key for throwing a bolt which moves a slidable plate to a position to cover the slot and sight openings so that the mail cannot be surreptitiously removed from the box, the cover of the box being normally locked thereto.

To the attainment of the foregoing the invention consists in the improvement hereinafter described and definitely claimed.

In the drawings:

Figure 1 is a face view of a letter box in accordance with this invention.

Figure 2 is a similar view but showing the slide moved downwardly to open the slot and to disclose the names of the several occupants of the residence to the mailman.

Figure 3 is a sectional view on the line 3—3 of Figure 2.

Figure 4 is a sectional view approximately on the line 4—4 of Figure 3, looking in the direction of the arrows.

Figure 5 is a detail approximately central transverse sectional view through the lower portion of the mail box.

The box 1 is preferably of substantially rectangular formation and has its edges, at its open face inwardly flanged, as at 2. The front or cover for the box comprises a plate 3 which is hinged, as at 4, to one of the corners of the mail box, and the front 3 may and preferably has its edges flanged, as at 5, to contact with the top and bottom and outer edge of the box 1. The inner face of the cover or door 3, adjacent to the edges thereof

is provided with guides 6 for a plate 7 that provides the slide of the improvement. The lower edge of the plate is formed with an angle lip 8, and the outer face of the plate is provided with a plurality of pockets for the reception of name bearing cards 9, the said cards designed when the slide 7 is in lowered position to register with sight openings 10 in the front or cover 3 and to likewise uncover a slot 11 in the said front or cover. The front or cover is provided with a pocket for the reception of a card 12 bearing the name of the housekeeper, manager, or owner of the dwelling on which the box is secured, the said card being at all times visible through a sight opening 13 in the said front or cover 3.

Secured to the inner face of the cover there is a lock casing 14 whose bolt is indicated by the numeral 15. The cover carries a key hole opening 16 for the lock and the key 17 which operates the bolt 15 is designed to be held in the possession of the mailman. A key operated lock 18 normally holds the front or cover 3 in closed and locked position on the box 1.

The slide 7 is of sufficient weight to normally gravitate downwardly through the guides 6 and to have its lip 8 rest on the top of the lock casing 14. When in such position the several cards 9 will appear opposite the sight openings 10 and the slot 11 will be uncovered. The mailman thus has visible knowledge regarding the occupants of the dwelling and mail matter for such occupants or for the housekeeper, manager or owner is inserted through the slot 11 into the box and thereafter the mailman turns the key to throw the bolt 15 which moves the slide 7 upwardly, causing the same to cover all of the said openings 10 and the slot 11. The mail is thus fully protected so that the same cannot be surreptitiously taken out of the box. When the lock 18 is operated by the owner of the box the mail matter may be removed therefrom. It should be stated that two keys 17 are employed, one of which is held by the mailman and the other by the housekeeper or manager and after the mail matter is removed from the box the lock 14 is operated to move the bolt into the lock casing to permit of the slide gravitating downwardly to bring the name

cards 9 again in register with the sight openings 10 and to likewise uncover the slot 11 so that on his next trip the mailman can insert other mail matter into the box.

5 While I have illustrated a satisfactory embodiment of my improved device my features of invention are capable of extended application and I do not wish to be limited to the specific structure herein shown and described 10 and therefore, hold myself entitled to make such changes therefrom as fairly fall within the scope of what I claim.

Having described the invention, I claim:

15 1. A mail box having a hinged and normally locked cover for the open face thereof, and which cover is provided with a slot and with a plurality of sight openings, a name card carried by the cover opposite one of the sight openings, a gravity influenced slide- 20 able plate on the inner face of the cover carrying name cards to align with the remaining sight openings and to uncover the slot when the said slide moves downwardly and a key operated bolt to engage with the lower edge 25 of the slide to move and sustain the same in a position to cover the sight openings and the slot.

30 2. A mail box having a hinged and normally locked cover for the open face thereof, and which cover is provided with a slot and with a plurality of sight openings, a name card carried by the cover opposite one of the sight openings, a gravity influenced slide- 35 able plate on the inner face of the cover carrying name cards to align with the remaining sight openings and to uncover the slot when the said slide moves downwardly, a lip on the lower edge of the slide, a key operated lock fixed in the casing and the bolt of the lock being mov- 40 able to contact with the lip to raise the slide to cause the latter to cover the sight openings and the slot.

In testimony whereof I affix my signature.
NASEEB A. NADDAFF.
